UNITED STATES PATENT OFFICE.

RENÉ CLAVEL, OF BASEL, SWITZERLAND.

PROCESS OF SIZING PAPER.

1,211,288.

Specification of Letters Patent. Patented Jan. 2, 1917.

No Drawing.

Application filed August 12, 1916. Serial No. 114,583.

To all whom it may concern:

Be it known that I, Dr. RENÉ CLAVEL, chemist, a citizen of the Swiss Republic, and resident of Basel, Switzerland, have 5 invented a new and useful Process for Sizing Paper, of which the following is a full, clear, and exact specification.

The treatment of paper in the course of its manufacture with size lends it strength, 10 luster and, according to the mode of treatment, a certain impermeability to moisture, water, acids, gases and the like.

The treatment consists in adding a solution of resin and salts of alumina to the 15 paper pulp in the hollander; or the paper is treated with solutions of resin, glue or the like, and, for the purpose of fixing the latter, with solutions of aluminium sulfate, aluminium acetate, hydrated alumina, or the 20 like, and then dried. Soap solutions are generally used as further fixing agents, whereby an insoluble alumina soap is precipitated on the paper, so that more complete waterproofing is attained. Again, 25 animal glue and casein are used, these adhesives being fixed by means of alums, chromates, formaldehyde or the like, whereby the paper becomes applicable for various purposes. By the present invention these 30 several sizing and fixing agents are applied in the form of foam-baths; for example the bath is caused to foam by means of compressed air or other gas diffusing from porous bodies in the bath at any temperature.

35 The foaming may be produced in any suitable vessel which contains the sizing or fixing liquid and has at its lower part one or more finely porous bodies, such as pipes or plates of burnt clay or graphite, through 40 which the compressed air or other gas can be diffused in the liquid in such manner that foam is formed in the upper part of the container; the paper web to be sized is brought into contact on one or both sides 45 with this foam by drawing the paper through the upper part of the vessel containing the foam.

The following examples illustrate the invention:

50 Example I: The paper, either on the machine or after it has left the machine, is brought into contact on one side, or is completely surrounded, with a resin size solution of the usual concentration which has

been brought into the condition of foam 55 in the aforesaid manner. After partial or complete drying, the paper is treated with a foam bath made in the aforesaid manner from a solution of aluminium sulfate of the usual strength for fixing the resin size and 60 containing some saponin.

Example II: The paper, either on the machine or after it has left the machine is treated with foam produced in the aforesaid manner from a solution of aluminium sulfate, of the usual concentration, containing some saponin; after partial or complete drying the paper is then treated with the foam from a soap-bath of the usual concentration. 70

Example III: A paper web which has been treated in the aforesaid manner with glue, casein or the like in the form of a foam-bath, is drawn through a foam made from an aqueous solution of formaldehyde, containing saponin, by means of carbon dioxide under pressure as already described. 75

Example IV: A paper web which has been treated with a foam-bath of glue, casein or the like in the aforesaid manner, is 80 drawn through a foam produced by causing gaseous formaldehyde to diffuse through a porous body into water containing saponin.

In both Example III and Example IV 85 the treatment with the formaldehyde foam-bath may precede the treatment with glue, casein or the like.

Together with the foam-baths named above there may be applied to the paper 90 with advantage other materials necessary for waterproofing or softening it, such as caoutchouc, wax, paraffin-wax, glycerin or the like, since the foam bubbles are adapted to carry these materials emulsified in a 95 very fine state of subdivision and to distribute them on the paper uniformly owing to the constant movement of the bubbles. For instance, to the aluminium sulfate solution used in Example I may be added more 100 or less of a solution of 1.5 kilos of caoutchouc, ceresin or paraffin-wax and 1.25 kilos of glycerin in a mixture of 2 kilos of oil of turpentine and 4 kilos of strong alcohol.

The invention permits of obtaining uniform sizing with a considerably smaller amount of chemicals and smaller baths than hitherto usual, since the foam bubbles satu- 105

rate the paper mass uniformly. Moreover, the easily torn paper webs are essentially preserved and waste reduced.

What I claim is:

- 5 1. A process for sizing paper wherein the sizing and fixing baths are applied to the paper mass or the paper, in the form of foam, substantially as described.
- 10 2. A process for sizing paper wherein there is applied to paper which has been treated with glue, casein or the like, a fixing

bath in the form of foam produced by diffusing gaseous formaldehyde through a liquid adapted to foam, substantially as described.

In witness whereof I have hereunto signed 15
my name this 21st day of July, 1916, in the
presence of two subscribing witnesses.

DR. RENÉ CLAVEL.

Witnesses:

ARNOLD ZUBER,
AMAND RITTER.
